UNITED STATES PATENT OFFICE.

NUTTER W. MURPHY, OF CEDAR JUNCTION, KANSAS.

WASHING-MACHINE.

SPECIFICATION forming part of Letters Patent No. 255,446, dated March 28, 1882.

Application filed January 13, 1882. (Model.)

To all whom it may concern:

Be it known that I, NUTTER W. MURPHY, a citizen of the United States, residing at Cedar Junction, in the county of Johnson and State of Kansas, have invented certain new and useful Improvements in Washing-Machines, of which the following is a specification, reference being had therein to the accompanying drawings, and in which—

10 Figure 1 is a plan view, Fig. 2 is a cross-section, and Fig. 3 is a longitudinal section, of my improved washing-machine.

This invention appertains to that class of washing-machines in which provision is made 15 for the escape of the surplus water and compressed air from under the plunger in its downward stroke to act on the fabrics, the plan heretofore adopted to effect this result consisting in fastening spaced-apart ribs of a semicircular form to the bottom, ends, and sides of the clothes-receptacle.

The nature of my invention consists in the employment, in connection with a vessel or tub, 20 of a lining adapted to conform to the bottom, ends, and sides of the vessel, and composed of a series of spaced-apart slats and a plunger adapted to fit and work in the vessel or tub, and provided with means for its operation, substantially as hereinafter more fully set forth 25 and claimed.

To carry out my invention I employ a vessel or tub, preferably made of metal to adapt 30 it for heating water preparatory to washing. It is also made preferably rectangular in shape, 35 and provided with hand-holds *a* for its convenient handling and outlet-pipe *a'* to pass off the dirty water after washing.

B is a lining, composed of spaced-apart bottom pieces or slats, *b*, and spaced-apart vertical 40 end and side pieces or slats, *b'*, united to the bottom pieces and to a frame, *b²*, at their upper ends. This lining is thus adapted to fit into and conform to the inside of the vessel or tub *A*, and may rest on longitudinal strips or 45 bars placed in the bottom of the vessel or tub *A*.

The purpose of this lining, composed principally of slats with intermediate spaces, is to provide for the escape from under the plunger, 50 presently described, of the compressed air and surplus water during the downward stroke of the plunger as it acts on the fabrics, the air and water rushing into the intermediate spaces

between the slats, and the water flowing over the plunger to permit it to flow back upon the fabrics during the upward stroke of the plunger to be again used.

c is a frame screwed or otherwise secured upon the outer upper edge of the vessel or tub *A*, the screws or other fastenings thereof passing through the vessel and into the frame *b²* of the lining *B* to also secure the lining in position in the vessel or tub.

C is the plunger, constructed preferably of an imperforate board, rectangular in shape to adapt it to fit into and work in the vessel or tub, and having a downward-projecting flange, *C'*, on its under side, arranged around its outer edge. The plunger *C* has fixed to its ends two upwardly-extended arms, *d d*, each hung at its upper end between two parallel bars, *e*, of a frame or lever, *D*, pivoted at its rear end, preferably by means of a rod, *e'*, to bars *E*, fastened upon the frame *c*, and having their rear ends supported in an elevated position by means of standards *f*, fastened thereto and 55 passed down through apertures in the frame *c*, and into sockets *f'*, formed upon or supplied to the vessel or tub *A*. The fulcrum or rod *e'* of the lever or frame *D* is capable of adjustment, as are also the fulcrums or pivotal pins 60 of the plunger-arms *d*, by means of serial perforations to vary the stroke and leverage of the plunger as may be required. *g g* are two other standards fastened to the rear side of the frame *c*, and having their upper ends each 65 extending up between the parallel bars *e* on its side of the machine, and the fulcrum-rod of the lever *E* passed through it to strengthen and render more substantial the fulcrum-point of the lever. The lever-frame *E* has a handle, 70 *E'*, to permit of its convenient manipulation in operating the plunger.

The operation of the machine is obvious, as by reciprocating the plunger it will be caused to act on the fabrics in the tub *A*, and by this 75 action, in connection with that of the water, the cleansing of the fabrics will be effected.

This lining can be readily removed for 80 repairs or other purpose by withdrawing the screws securing it to the frame at the top of 85 the receptacle.

I claim and desire to secure by Letters Patent—

In a washing-machine, the lining composed

of spaced bottom slats and spaced vertical end and side slats detachably secured to a surrounding upper frame, all adapted to fit into and conform to the inside of the tub, in combination with the plunger adapted to operate therein, its operating devices, and the tub or vessel adapted to be used either on or off of the stove, as and for the purpose set forth.

In testimony whereof I affix my signature in presence of two witnesses.

NUTTER W. MURPHY.

Witnesses:

CHRIS WAGNER,

MARY J. WAGNER.
